DEVICE AS AN AID IN SHOE FITTING

Imla E. Hewitt, Jr., Springfield, Ill.

Application March 17, 1941, Serial No. 383,664

2 Claims. (Cl. 33—3)

This invention pertains to a device for use in more readily and correctly providing for the proper size of foot wear for a given length of foot. More particularly, the invention involves a device by which to denote the correct length and fit of a shoe, especially women's shoes having high heels.

An object is to furnish a foot support inclined at an angle downwardly and forwardly and whose highest or heel portion may be made to correspond in height to the heel-height desired to be worn by the patron whereby the foot by body-weight thereon will show its particular characteristics so that the proper size and form of shoe having that height of heel may be correctly chosen.

Another object is to furnish such a support with means for adjusting the heel portion thereof for any predetermined height of heel to be worn, and to include with the same a scale or scales of measurement by which the proper shoe size is automatically determined.

That the invention may be understood the appended drawing is provided showing a manner of accomplishing the objects named, it being understood, however, that changes may be made in the structure such as may fall within the claims to follow.

Figure 1 is a side elevation of the device.

Figure 2 is a plan of the same.

Figure 3 is a front elevation of the device, part being shown in section taken on line 3—3 of Figure 2.

Figure 4 is an elevation, enlarged of a scale-board best shown in Figure 1.

Figure 5 is an enlarged plan of a scale also shown in Figure 1, and

Figure 6 illustrates in perspective a shiftable stop-member shown in Figure 2.

The human foot being flexible due to its bone formation is capable both of shrinkage and elongation. The weight of the body upon the foot naturally distributes the pressure fairly evenly throughout when the center of the weight is substantially directly above the foot's middle length so that the heel and the ball receive substantially the same pressure, the toes in a smaller degree also being part of such weight. This condition obtains, of course, when the foot is resting upon a flat horizontal surface. However, when the heel of the foot is raised the body weight is shifted thereto in order to maintain balance, the foot tends to shift forwardly, or to elongate, due to the named flexibility.

Women's shoes of the high heel type cause the

foot to elongate thus requiring a shoe of a length to agree with the measurement of the foot so elongated in order that entire comfort may be afforded, besides preventing wear occasioned by a shoe that is too short.

The device herein to be described is so provided, therefore, that shoes of the high heel type may have the proper fit and provide permanent comfort.

10 In the figures of the drawing a supporting base member 1 is provided, somewhat longer than the foot to be fitted, and extending above which is a portion 2 to which, at one end, is hinged a foot-supporting part 3. Means is provided for 15 locating the free end of the said part 3 at any desired elevation with respect to the upper surface of the portion 2. While any good manner of accomplishing this may be employed, there is here shown, as an example, a slotted arm 4 at each side of said part 3, each having within its 20 slot 5 a series of projections 6 each to form a stop or retainer for a pin or stud 7 extending from said part 3. Each arm 4 is suitably pivoted at one extremity relative to the said base 1 so that each is free to swing in its own plane as 25 the pins or studs 7 rise or fall in adjusting the part 3.

Arising from the rear or heel extremity of the latter is an arcuate guard 8, for example, that 30 may, when desired, receive the back of the foot to be measured and fitted.

At the toe-end of the device the top surface of the portion 2 is preferably furnished with markings 9 for foot size to indicate the length of a 35 foot at the great toe or the overall distance from the back of the heel position of such foot at the guard 8 to the toe end.

Mounted to move along opposite the scale markings 9 is a stop-member or gauge shown 40 most clearly in Figure 6. This may comprise a block 10 having a curved face to receive into it the end of the great toe, and having an extension 11 to act as a pointer in respect to the scale markings.

45 This gauge may be freely shiftable over the surface of the portion 2 or it may include a feather or fin 12 depending below it adapted to engage in a slot 12' in said portion 2 paralleling the indicated scale measurements, such slot lying 50 in line with the great toe position for guiding the gauge positively.

In proper shoe fitting it is important to know the great toe's length or the distance it extends from the ball of the foot. To this end erected on the base 1, for example, is a scale-board 13

having on its vertical inner face a series of markings denoting sizes, the numeral "4" of the markings lying nearest the rear end of said board while "13" lies forward thereof as shown in Figure 4 of the drawing. By means of this scale the fitter of a shoe may determine the length of the great toe and that length with respect to the total length of the foot including said toe, and thus be guided in the choice of shoe to fit any given foot.

Naturally, due to the weight of the standing person whose foot is to be measured the foot is inclined to slide forward due to the inclined support 3. To offset the tendency to thus shift the support may be provided with a covering of sponge rubber or its equivalent in order to provide a friction surface.

In use, the support 3 is adjusted to the height of the heel of the chosen type of shoe, whereupon the foot of the standing person is placed in position with the heel abutting the guard 8. Following this the gauge 10 is brought to close adjustment at the great toe. The reading on the scale is then taken as indicated by the extension or pointer 11 together with the reading of the scale on the board 13 for toe-length measured from the ball of the foot, whereupon the attendant is apprised of the size of the shoe and its peculiarity for that particular fitting.

With the foot bearing upon the device the ball thereof may be at the hinging point of the portions 2 and 3 with the heel abutting the guard 8 when the test is made for the required shoe. However, a foot of any shorter measurement may be readily accommodated without having the ball thus placed since it may be even forward of the hinge or rearward thereof so far as consideration of foot length is concerned. Since a friction surface is provided the foot will not slip forward in its tipped position but the foot bones under imposed weight will change in their relation the overall length. That is to say, due to the structure of the bones and their relation to each other the foot becomes longer as the heel supporting portion is increased in height and angularity. Otherwise stated, since the foot includes an arched bone-structure which flexes under body-weight, such structure admits of flattening of the arch of the foot causing an overall lengthening of the same which does not occur in so marked a degree when the foot rests wholly upon a horizontal surface where the weight bears directly downward through the heel.

The measurement for the lengthened foot is then taken at the markings at 9 assisted by the gauge 10 if desired, and for any size of foot. Toe lengths vary as between the feet of individuals having the same overall foot-length; however,

and the markings at 13 are convenient in that since ready-made shoes vary in characteristics, i. e., shorter or longer from the "ball" position to toe extremity, and even in the same shoe-size, the sales-person may observe the ball position of the foot being fitted and thus determine more nearly the type of shoe best suited to the given foot to the end that the most comfort may be afforded as contrasted to the usual manner of chance fitting often attended with much discomfort to the wearer of a shoe.

The gauge 10 need not be used, of course, and the scale markings 9 may lie in position on the portion 2 directly beneath the toe position, the reading from the scale being taken directly at the toe's end.

Further, the scale 9 may not necessarily be used even though indicated, since a measuring tape would serve the purpose of determining foot length. The same would be true with respect to toe-length and the scale-board 13.

Again, while the erected scale board 13 is convenient as described and shown the markings for such a scale might be placed upon the tread surface of the supporting parts 3 and 2 in the same manner as in the scale 9 of the latter.

I claim:

1. In a device as an aid in shoe fitting, the combination of a substantially horizontally disposed toe supporting portion, a heel supporting portion adjoining at one end the said toe portion and upwardly tiltable at various angles with respect to the same from a fixed point thereat, means to support said heel portion at any given height of inclination, a series of marks at the toe supporting portion for denoting distances from the rear extremity of the heel portion to the toe ends of a foot being fitted, and a series of marks for indicating the distance between the ball of said foot and the said toe ends of the foot.

2. In a device as an aid in shoe fitting, the combination of a substantially horizontally disposed toe supporting portion, a heel supporting portion adjoining at one end the said toe portion and upwardly tiltable at various angles with respect to the same from a fixed point thereat, means to support said heel portion at any given angle of inclination as the latter swings about said fixed point, a series of marks on the toe portion as indications of overall length of a foot to be fitted with a shoe, and markings on another part of the structure of the device, the line of markings paralleling the two named portions and lying both rearwardly and forwardly of the position of adjoining of said portions.
